US0D1091256S

(12) **United States Design Patent** (10) **Patent No.:** **US D1,091,256 S**
(45) **Date of Patent:** **** Sep. 2, 2025**

(54) **COLD STORAGE CONTAINER**

(71) Applicant: **Zhejiang Sunclose Technology CO., LTD.**, Jinhua (CN)

(72) Inventors: **Huajian Zhang**, Jinhua (CN); **Jingping Li**, Jinhua (CN)

(73) Assignee: **Zhejiang Sunclose Technology CO., LTD.**, Jinhua (CN)

(**) Term: **15 Years**

(21) Appl. No.: **29/929,475**

(22) Filed: **Feb. 22, 2024**

(30) **Foreign Application Priority Data**

Jan. 31, 2024 (CN) 202430067176.3

(57) **CLAIM**

The ornamental design for a cold storage container, as shown and described.

DESCRIPTION

FIG. 1 is a front, left and top perspective view of a cold storage container, showing our new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the cold storage container that form no part of the claimed design.

1 Claim, 8 Drawing Sheets
